UNITED STATES PATENT OFFICE.

PETER C. BURNS, OF CHICAGO, ILLINOIS, ASSIGNOR TO AMERICAN ELECTRIC TELEPHONE COMPANY, OF CHICAGO, ILLINOIS, A CORPORATION OF NEW JERSEY.

ELECTRIC FUSE.

1,109,036.

Specification of Letters Patent.

Patented Sept. 1, 1914.

Application filed September 14, 1905. Serial No. 278,380.

To all whom it may concern:

Be it known that I, PETER C. BURNS, a citizen of the United States of America, and resident of State and Sixty-fourth streets, 5 Chicago, Illinois, have invented a certain new and useful Improvement in Electric Fuses, of which the following is a specification.

My invention relates to electric fuses in 10 general, but more particularly to fuses in which the fusible material is embodied in a structure which is readily removable from the supporting devices, and especially to the so-called tubular type of electric fuse,—that 15 is to say, a fuse of that type in which the fusible wire or conductor is inclosed in a tubular member having its ends adapted to removably engage the supporting and conducting devices.

Generally stated, the object of my invention is to provide an improved and highly efficient electric fuse.

Special objects of my invention are to provide a fuse of such character that the 20 fusible wire or conductor can be adjusted in place without making any solder connections; to provide a fuse of such character that the fusible wire or conductor can be readily and quickly adjusted into electrical 25 connection with the heads or metallic terminal members of the tube or tubular inclosing member through which it extends; to provide a fuse of such character that the fusible wire or conductor may have its end portions 30 electrically connected with the heads or metallic terminals of the tubular member by means of split metal plugs around which the end-portions of the fusible wire are wrapped and which may then be forced into the 35 ends of the bore of the tube, thus obviating the necessity of soldering the said end-portions of the wire to the said heads or metallic terminals; and to provide certain 40 details and features of improvement tending 45 to increase the general efficiency and serviceability of an electric fuse of this particular character.

To the foregoing and other useful ends, my invention consists in matters herein- 50 after set forth and claimed.

In the accompanying drawings, Figure 1 is a longitudinal section of an electric fuse embodying the principles of my invention. Fig. 2 shows one end-portion of the fuse 55 shown in Fig. 1, and illustrates a method of

electrically uniting the end of the fuse wire with the head or metallic terminal of the tubular fuse. Fig. 3 is an end view of the fuse shown in Fig. 1. Fig. 4 is a cross-section on line 4—4 in Fig. 1. Fig. 5 is a cross-section on line 5—5 in Fig. 1. Fig. 6 is a perspective of one of the fuse wire terminal plugs.

As thus illustrated, my improved electric fuse comprises a tube A which is preferably 60 of wood or other insulating material, and which has a longitudinal bore a and a transverse opening or bore a', the two bores intersecting each other at a point substantially mid-way between the two ends of the tube. 65 The heads or metallic terminals B are secured upon the end-portions of the tube, as by pinching or pressing in the small portions b, and are provided with reduced or neck-like portions b' adapted to engage any 70 suitably notched springs or posts or other metallic supporting and conducting devices upon which the tubular fuse is adapted to be 75 removably supported. It will be seen that these metal heads or terminals B are each 80 provided with a bore or opening b² which registers with the bore or longitudinal passage a of the tube. In each case, the metal heads or terminals B are provided with lateral and longitudinally extending notches 85 or grooves b³ which open through the sides of the neck portions b', as shown more clearly in Fig. 4.

The fusible wire or conductor C may be 90 of any suitable known or approved material, and of any suitable resistance, according to the character and uses of the circuit in which it is included. The said fusible wire has its end-portions wrapped around the shanks or cylindric body-portions of the 95 fuse wire terminal plugs D. It will be seen that each of these plugs is preferably of the character shown more clearly in Fig. 6—that is to say, consists of a cylindric shank or body-portion d tapered at its point or 100 end and provided with a split or notch d', the latter extending substantially for its full length. In other words, this split or notch extends nearly to the head d² of the plug, so that when inserted in the bore of one of 105 the heads or terminals B, and crowded down therein, the two portions of the shank or body-portion are flexed together, thus insuring a constant spring or resiliency sufficient to keep the plug in place and insure 110

a good electrical contact with the head or metal terminal B. After the fusible wire or conductor C is threaded through the bore *a* of the tube A, its end-portions are then wrapped around the shank or cylindrical body-portions of the terminal plugs, as shown in Fig. 2, or the protruding end-portions can be simply bent to one side. After this the two plugs are then forced toward each other and into the bore extending through the structure as a whole, with the result that the end-portions of the fusible wire are crowded into tight contact with the inner surface of the metal heads or terminals B, as shown in Fig. 1. This is possible, of course, by reason of the adaptability of the two parts or prongs of the plug to spring together, as it is pushed into the bore; and the constant tendency of the plug to expand laterally then tends to keep it in place and insure a perfect electrical contact or joint between the fuse wire and the head or terminal of the tubular fuse. In this way, the fuse wire can be adjusted into place without the use of solder, and without the necessity of soldering any of the different parts together, or of resorting to other similar attaching means. The fuse wire when adjusted into place can always be readily removed for the purpose of inspection, and a burned-out fuse is very easily repaired. When the terminal plugs D are in place, as shown in Fig. 1, the end-portions of the fuse wire within the bore of the heads or terminals B are crowded to one side and lie in the notches or grooves *b*¹, as shown more clearly in Fig. 4. In this way, the heads *d*² of the said terminal plugs bear down upon the coiled-up end-portion of the fuse wire, and hold the same tightly upon the outer ends of the metal terminals B, thus insuring a good electrical connection between the fuse wire and the two terminals.

45 What I claim as my invention is:

1. An electric fuse comprising metallic terminal members, a body member upon which said terminal members are mounted, a fuse wire, and removable longitudinally split metal plugs securing the end-portions of the fuse wire to and within the said terminal members, said plugs removable outwardly from the ends of the terminals.

2. An electric fuse comprising metallic terminal members, a body member upon which said terminal members are mounted, a fuse wire, and removable longitudinally split metal plugs securing the end-portions of the fuse wire to the said terminal members, the wire being coiled around each plug, said plugs having their bifurcated ends extending toward each other.

3. An electric fuse comprising a tube of insulation, grooved metal terminals secured to the end-portions of the tube and provided

with openings registering with the bore thereof, a fuse wire extending through the tube and grooves of the terminals, and metal plugs fitting within the said terminals and holding the ends of the fuse wire in electrical contact therewith. 70

4. An electric fuse comprising a tube of insulation, grooved metal terminals secured to the ends of said tube, a fuse wire extending through the tube and lying in the grooves of the terminals, and longitudinally split metal plugs fitting within the ends of said terminals and holding the fuse wire in close electrical contact therewith. 75

5. A tubular fuse provided with a longitudinally extending fuse wire, and having its ends provided with internally grooved metal terminals to which the end-portions of the said fuse wire are removably and electrically connected, the wire lying in the grooves thereof, and means for holding the wire in the grooves. 80

6. An electric fuse comprising a tube of insulation, a fuse wire extending through the bore of said tube, grooved metallic terminals secured to the ends of said tube, and plugs fitting within the ends of said terminals and securing the ends of the fuse wire thereto, with the wire lying in the grooves thereof, said insulating tube having a transverse opening therein exposing said fuse wire, said plugs removable outwardly from the ends of said terminals. 90 95

7. A tubular fuse provided with a longitudinally extending fuse wire, and having its ends provided with internally grooved metallic terminals to which the end-portions of the said fuse wire are removably and electrically connected, with the wire lying in the grooves thereof, said tube having a transverse opening therein exposing said fuse wire. 100 105

8. A fuse comprising a tube of insulation, metal caps for the ends of said tube, provided with openings extending in continuation of the bore of said tube, a fuse wire extending through the base of said tube and projecting through the said openings, and metal plugs inserted in said openings with their ends pointing toward each other, the end portions of said fuse wire being wound around the outer ends of said plugs, each plug having a head to hold the coiled wire in place on the metal cap. 110 115

9. A fuse comprising a tube of insulation, metal caps for the ends of said tube, provided with openings extending in continuation of the bore of said tube, a fuse wire extending through the base of said tube and projecting through the said openings, and metal plugs inserted in said openings with their ends projecting toward each other, the end portions of said fuse wire being wound around the outer ends of said plugs, each plug having a head to hold the coiled wire 120 125 130

in place on the metal cap, each metal cap provided with an interior longitudinal groove in which the wire is held by the side of the plug.

- 5 10. A fuse comprising a tube of insulation, metal caps for the ends of said tube, provided with openings extending in continuation of the bore of said tube, a fuse wire extending through the base of said tube and projecting through the said openings, and metal plugs inserted in said openings with their ends pointing toward each other, the end portions of said fuse wire being wound around the outer ends of said plugs, each plug having a head to hold the coiled wire in place on the metal cap, each plug being pointed and split for a portion of its length to provide springy portion which yield when the plug is inserted in the cap.
- 15 11. A fuse comprising a fuse-wire, plugs pointing toward each other and around

which the end portions of the wire are wound, terminals in which the plugs are inserted, and insulation between said terminals, each metal terminal provided with an 25 interior longitudinal groove in which the wire is held by the side of the plug.

12. A fuse comprising a fuse-wire, plugs pointing toward each other and around which the end portions of the wire are 30 wound, terminals in which the plugs are inserted, and insulation between said terminals, each plug being pointed and split for a portion of its length to provide springy 35 portions which yield when the plugs are inserted in the terminals.

Signed by me at Chicago, Illinois, this 12th day of Sept. 1905.

PETER C. BURNS.
